UNITED STATES PATENT OFFICE.

EDWARD GERMAIN, OF SAGINAW, MICHIGAN.

DESIGN FOR A MANTEL.

SPECIFICATION forming part of Design No. 21,158, dated November 10, 1891.

Application filed October 14, 1891. Serial No. 408,726. Term of patent 7 years.

To all whom it may concern:

Be it known that I, EDWARD GERMAIN, of Saginaw, in the State of Michigan, have invented and produced a new and original Design for Mantels, of which the following is a specification.

In the accompanying drawings, Figure 1 represents the mantel in front elevation. Fig. 2 is a transverse vertical sectional elevation of the same. Fig. 3 is a cross-section of one of the pilasters.

The sectional views are intended not to exhibit the mechanical construction of the mantel, but to better illustrate the outline and configuration of the several parts of the mantel.

a are the pilasters; *b*, are the plinths; *c*, the brackets or dentals; *d*, the mantel-board; *e*, the frieze; *f*, the grounds, and *g* the fire-strips. 20 Upon the grounds *f* are raised vertical backing strips or panels *h*, having their longitudinal edges beveled, as at *i*. Upon these raised vertical backing strips or panels are the pilasters, plinths, and brackets or dentals. Each 25 pilaster has its outer face molded, as shown in Fig. 1, and in cross-section, Fig. 2, where the outline of the molding is plainly exhibited. The plinths are thicker and wider than their pilasters, thus projecting beyond the 30 latter in front and at the sides. The upper portion of each plinth is molded, the molding

consisting of an upper bevel *b'*, a lower bevel *b''*, and an intermediate ogee-shaped surface *b'''*.

The configuration of the brackets *c* in side elevation is shown in Fig. 2. Each bracket 35 has on its face two cross V-grooves *c'* *c''*, and longitudinal grooves or dents *c'''* extending between these cross-grooves.

The frieze *e* is flush with the backing-strips or panels *h*, and upon it is the raised panel 40 *j*, having a continuous concave beveled border *k*. The lower edge of the frieze is beveled, as at *l*, and beneath it is the molding *m*.

Beneath the mantel-board is a molding *n*, which extends around the tops of the brackets *c* also, and below this molding *n* is another 45 molded strip *o*, which extends between the brackets.

The edges of the mantel-board, as well as the fire-strips and the outside edges of the 50 grounds *f*, are molded, as shown.

What I claim, and desire to secure by Letters Patent, is—

The design for a mantel, as herein described and shown.

In testimony whereof I affix my signature in presence of two witnesses.

EDWARD GERMAIN.
